PORTABLE HEAD RESTS AND BLANKS
THEREFOR
Calvin T. Kinsman, 700 Sunset Blvd.,
New Port Richey, Fla.
Filed Aug. 23, 1963, Ser. No. 304,182
6 Claims. (Cl. 297—397)

This invention relates to portable head rests of the class which includes a structure which may be selectively positioned upon or removed from the back of a vehicle seat, for example, so that when the structure is so positioned it will augment the height of the seat back, whereupon the head of an occupant of the seat may rest against the structure. Furthermore, the invention is of the class disclosed in my United States Letters Patent 2,996,333, dated August 15, 1961, for Portable Head Rests, and my United States Letters Patent 3,017,222, dated January 16, 1962, for Portable Head Rest.

An important object of the present invention is to provide portable head rest structures which include forwardly-positioned concave portions constructed and arranged to be engaged by the back portion of the user's head rather than the back of the head engaging the main portion of the structure, whereby an especially comfortable head rest is provided.

Another important object of the invention is to provide portable headrest structures as last described above in which the forwardly-positioned portions are detachably connected and may be removed and they and the main portions collapsed and flattened out in order to conserve space.

A further object of the invention is to provide portable head rest structures each of which initially embodied a single length of suitable sheet material, provided with openings, tabs, fold lines and a weakened portion in order to permit separation of a part thereof, and both parts manipulated so as to provide the structure described above.

The head rest structures of this present invention are of such low cost in manufacture and for sale that they may be regarded as disposable after limited use; and the blanks may be readily shipped and stored flat (stored as by a dispenser thereof, i.e., motor fuel dealer, or disposed under a car seat for example); may contain advertising or other indicia; used in promotion or as give-away items; and may be readily assembled for use by the average person, since assembling thereof is relatively simple.

Other objects and advantages of the invention will be apparent during the course of the following detailed description of the invention, taken in connection with the accompanying drawings, forming portions of this disclosure, and in which drawings:

FIG. 1 is a plan view of one form of blank adapted to provide one form of portable head rest structure.

FIG. 2 is a perspective view of the blank of FIG. 1 formed into a portable head structure in use.

FIG. 3 is a transverse sectional view, substantially on the line 3—3 of FIG. 2.

FIG. 4 is a plan view of another form of blank adapted to provide a second form of portable head rest structure.

FIG. 5 is a perspective view of the blank of FIG. 4 formed into a second portable head rest structure.

FIG. 6 is a transverse sectional view, substantially on the line 6—6 of FIG. 5.

FIG. 7 is a plan view of a third form of blank adapted to provide the form of portable head rest of FIG. 8.

FIG. 8 is a perspective view of the blank of FIG. 7 formed into the portable head rest structure of FIG. 7.

FIG. 9 is a transverse sectional view, substantially on the line 9—9 of FIG. 8.

In the drawings, wherein for the purpose of illustration

2

are shown three forms of blanks and three forms of portable head rest structures, the letters A, C and E may designate the blanks of FIGS. 1, 4 and 7 respectively; the letters B, D and F may designate the head rest structures of FIGS. 2, 5 and 8 respectively; the letters G, H and K may designate seats upon the backs of which the structures B, D and F may be mounted, and the letters L, M and N may designate the users of the structures B, D and F while occupying the seats G, H and K respectively.

The blanks A, C and E have, in common, the following features: They each consist of a single elongate sheet of self-sustaining, readily-stamped or die-cut material which may be scored so as to be readily bent or folded, and provided with a weakened portion so as to effect ready separation of the blank into two portions. The blank is capable of being arched as will be subsequently described. The material may be fibre board, heavy cardboard, jute board and the like. While the length and width of the blank may vary, an overall length of substantially 40 inches and a width of substantially 8 inches may be given by way of example. However, as noted in FIGS. 4 and 7, the overall lengths of the blanks may differ from the example given above. Each blank is provided with a plurality of slots, an elongated tongue, a plurality of tabs provided with tongue portions, and preferably minor cutouts where small discarded portions of the material are removed in the stamping or die-cutting.

Referring particularly to FIG. 1, the blank A has substantially parallel partial side edges 10 extending to preferably rounded edges 11, curved side edges 12, tab edges 13, 14 and 15 and tongue edges 16 to 20. Material, designated as 25 to 28 with broken lead lines, is material removed in the stamping or die-cutting step. There are also end edges 29 and 30.

A pair of substantially parallel, transversely-extending slots 35 are preferably provided adjacent the edge 29 and preferably two pairs of longitudinally-extending axially-aligned spaced-apart openings or slots 36, adjacent the mid portions of the side edges 10, and a transversely-extending centrally-disposed slot 37, adjacent one slot 36 of each pair. These slots 36 and 37 are arranged to have their walls form a portion of means 66 for connecting the forwardly-positioned portion 56 of the head rest structure B to the main portion thereof. While the provision of the four slots 36 and slot 37 insures a very acceptable arrangement for the attachment of the forwardly-positioned head rest portion 56 to the main head rest portion 55, I may provide one slot 36 adjacent each edge 10, or omit the slot 37, or provide more than the four slots 36 or pairs of slots 37.

The blank A is also provided with a preferably elongated hinged tab 38 extending longitudinally thereof and fashioned by providing elongated longitudinal cuts 39 therethrough and a short cut 40 joining one like end of each cut.

Curved fold lines 45 and 46 and substantially straight fold lines 47 to 52, and narrow weakened portions 53 are also provided for the blank A, substantially as shown in FIG. 1. The weakened portions 53 may be the walls of indentations or perforation or a series of short slits in the material of the blank A.

The blank A, when the portion thereof which will constitute the main head rest portion 55, is separated from the part thereof which will constitute the forwardly-positioned head rest portion 56 provides, when arranged as in FIG. 2, the head rest structure B. Except for the provision of the slots 36 and 37, the portion 55 may be much like the structure of the head rest of my Patent 3,017,222, referred to above. That is, there are provided a front part 57, a rear part 58, bridge 59, and curved part or hinge 60 joining the parts 57 and 58, with the bridge 59 (provided by the elongated tab 38) detachably joining

these parts 57 and 58. As may be seen in FIG. 2, the front part 57 includes two areas 67 and 68. Area 67 is the area contacted by the back of the occupant of the seat G using the head rest B, while the area 68 is the area above the area 67 and which faces the resilient head-contacting sheet of the forwardly-positioned portion 56, which sheet is spaced from the area 68 with a space between them. This permits uninterrupted arching of the sheet to provide a head-receiving concavity as will be explained subsequently.

As may be appreciated from FIGS. 2 and 3, the slots 36 and 37 are now in the front part 57 at the upper portion thereof.

Referring now to the forwardly-positioned head rest portion 56, after the weakened portions 53 are severed, the tabs 61, defined by the edges 13 and 14 and fold lines 51 and 52 respectively are folded in their respective fold lines to substantially parallel each other (as in FIG. 3) and the tab 62 defined by the edges 15 and 20 and the fold line 53 is folded on that fold line (as may be seen in FIG. 2), the tongues of the tabs 61 are inserted in the slots 36 and the tongue of the tab 62 inserted in the slot 37, with all fits of the tongues being intimate or tight, the forwardly-positioned head rest portion 56 is in position for use. The tabs 61 and 62 with their tongues cooperate with the walls of the slots 36 and 37 to provide means 66 for detachably connecting the portions 55 and 56 together.

Since the shortest distance between the fold lines 51 is somewhat greater than the shortest distance between opposite of the slots 36, as is clear in FIG. 1, the head-engaging area 68' of the forwardly-positioned portion 56 will provide a concavity 64. In FIG. 3, this area 68' is shown as faced with a sheet of resilient material 65, but the use of this is optional, and it may be omitted.

Comparing FIG. 2 with FIG. 1, it will be seen that especially the curved edge 12 projects upwardly and rearwardly. This, together with the curvature of the area 63 to form the concavity 64, provides a very restful total area for the head of the user L.

Canting of the forwardly-positioned head rest portion 56 is prevented by the use of the tab 62 which is, as shown in FIG. 1, relatively broad. The tongues of the various tabs are preferably short, being just sufficient to extend through the slots 36 and 37 and project very slightly therefrom.

The portable head rest structure A is positioned with the bridge 59 engaging the upper face 70 of the back 71 of the seat G, the front part 57 engaging the front face 72 of the seat back, and the rear part 58 disposed over the rear face 73 of the seat back.

With reference to the form of the blank C, of FIG. 4, this is much like the blank A, as was stated heretofore and similar reference numerals, followed by the exponent ', will be employed to designate parts of the blank C substantially corresponding to like parts of the blank A.

The essential difference between the blank C and blank A reside in the elimination of the slots 36 and substitution thereof of cuts through the materials of the blank C, at 70 to 76 inclusive, with fold lines 77 joining the cuts 70 and 76. These fold lines 77 are substantially parallel the side edges 10' and are adjacent thereto. In addition, I prefer to provide an additional transverse slot 78 opposite the slot 37', the walls of which function as do the walls of the slot 37.

Referring to the lower portion of FIG. 4 and the forwardly-positioned head rest portion 96 of FIGS. 5 and 6, the blank concludes the edges 80 to 85 inclusive, after removal of the surplus material 86 to 89. This lower portion also includes two longitudinally-extending openings or slot 90 adjacent and substantially paralleling the side edges 10', the walls of which, together with the tab defined by the edges 84, 85 and 18' and fold line 91, as well as the tab defined by the edges 82 and 83 and weakened portion 92, form portions of the means 91 for

connecting the forwardly-positioned head rest portion 96 to the main head rest portion 95 of the portable head rest structure D, next to be described.

With reference to the portable head rest structure D of FIGS. 5 and 6, when the blank C is divided into two parts along the weakened portion 92, there will be provided one part constituting a main head rest portion 95 and forwardly-positioned head rest portion 96.

The main head rest portion 95, when arranged as in FIG. 5, will be quite similar to the main head rest portion 55, and substantially similar parts of the head rest portion 95 which find their equivalent in the head rest portion 55 will be designated by like numerals followed by the exponent '. There are provided a front part 57', a rear part 58', bridge 59' and curved part or hinge 60' joining the parts 57' and 58' with the bridge 59' detachably joining the parts 57' and 58'. There is also an area 67'.

In attaching the forwardly-positioned head rest portion 96 to the main head rest portion 95, the two tabs 97 and 98 are bent down at their respective fold lines 99 so that their tongues will enter the slots 78 and 37' respectively, but first, the two tabs 100 (FIG. 6) defined by the cuts 70-76 and fold lines 77, are bent upwardly.

It will be noted, by comparing FIG. 4 with FIG. 6, that the shortest distance between the slots 90 is greater than the shortest distance between the fold lines 77 so that, in order to effect a good entrance of the tongues of the tabs 100 into the slots 90, the tabs 100 must be raised (which reveals the slots or openings 100a as in FIG. 6) and then spread so that their axes converge downwardly and this tends to cause arching of the forwardly-positioned portion 96 in order to provide a concavity 101 which functions as does the concavity 64. The head of the user M rests upon this comfortable concave area 68' which functions as does the area 68. Canting of the tabs 100 out of their positions as in FIG. 6 is prevented by the relatively broad tabs 97 and 98.

Positioning of the head rest structure D upon the back 105 is similar to the positioning of the head rest structure B, in that the bridge 59' resting upon the upper edge 106, the front part 57', engaging the front face 107 of the seat back of the rear part 58' at the rear face 108 of the seat back.

I prefer that the tongues of the tabs 100 be short so that they do not extend unduly into the concavity 101, substantially as is exemplified in FIG. 6.

The blank E of FIG. 7 is, in the main, much like that of the blank C and, preferably, the only difference resides in the cuts 110 to 118 inclusive, and the absence of the slots 37' and 78 of the blank C. But with the example of the blank C before one, it is believed now obvious that there may be provided less cuts in the material of the blank E, so that but one tongue be provided for each tab or, two tongues be provided for the tabs 100 of the blank C. Even more than two tongues per tab may be provided if found expedient. Fold lines 119 joint the cuts 110 and 118.

In the lower portion of FIG. 7 it will be noted that four openings or slots 120 are provided relatively arranged somewhat like the slots 36 of the blank A. A weakened portion 121 is provided to separate the blank E into two parts.

Parts of the blank E, substantially similar to like parts of the blanks A or C, will be given similar reference numerals, followed by the exponent ''.

When the blank E is arranged as in FIG. 8 there is provided the portable head rest structure F with a main head rest portion 125 and a forwardly-positioned head rest portion 126.

The main head rest portion 125 includes parts substantially similar to those of the main head rest portions 55 and 95 and these will be given reference numerals followed by the exponent '' as to the portion 125.

The forwardly-positioned head rest portion 126 of the head rest structure F relates to both the forwardly-positioned head rest portions 56 and 96 as to a head contacting concavity 130, (defined by an area substantially similar to the areas 68 and 68') similar to the concavities 64 and 101, due to the shortest distance between opposite slots 120 being greater than the shortest distance between the fold lines 119. This will cause arching of the forwardly-positioned portion 126 when the tongues of the tabs 131 are inserted in the slots 120 as in FIG. 9.

The walls of the slots 120 and the tabs 131 with their tongues constitute means 132 for connecting the forwardly-positioned head rest portion 126, to the main head rest portion 125.

Of course, the tabs 131 must be raised and swung on the fold lines 119 in order to position them for use. The raising and swinging motions will reveal the slots or openings 131^a of FIG. 9.

In each form of the invention, given by way of example, the forwardly-positioned head rest portions 56, 96 and 126 face the upper areas of the main head rest portions 53, 95 and 125 and each portion 56, 96 or 126 constitutes a resilient, concave sheet with no structure, such as padding, springs, fluid-filled pockets and the like, between it and the upper areas of the associated main head portion. Such is not necessary and would but add considerable expense in the manufacture of the portable head rest.

Various changes in the size, shape and arrangement of parts may be made to the forms of invention herein shown and described, without departing from the spirit of the invention or scope of the claims.

What is claimed is:

1. A portable head rest for a back of a seat, the back having a front face and an upper face, said portable head rest including an upwardly-extending front part having an area for contacting said seat back, at said front face, and for contacting a portion of the back of a garment worn by an occupant of such seat back and leaning against said front part, said front part also having a second area above the first-named area; a head-contacting part consisting of a sheet of resilient material spaced outwardly of and facing said second area; dual function means, carried by said front part and said head-contacting part, attaching said head-contacting part to the portion of said front part defined by said second area and for arching said head-contacting part toward said second area to provide a concavity for receiving the back portion of the head of said occupant; and means connected with said front part intermediate the height thereof for resting upon said upper face for sustaining said front part upon said seat back.

2. A portable head rest according to claim 1 char-

acterized in that said dual function means includes tabs, having tongues, carried by one of said parts and bridging between said front part and said head-contacting part at said second area of said front part, said other part having slots snugly receiving said tongues.

3. A portable head rest according to claim 2 characterized in that said slots are in said front part, disposed longitudinally thereof, adjacent side edges thereof and side-by-side, and said tabs extend inwardly from side edges of said resilient sheet, and the shortest distance between said slots is less than the shortest distance between said tabs when substantially in parallelism and when said resilient sheet is substantially flat.

4. A portable head rest according to claim 2 characterized in that said slots are in said resilient sheet, adjacent side edges thereof and side-by-side, and said tabs project forwardly from said front part with the shortest distance between said slots, when said resilient sheet is substantially flat, being greater than the shortest distance between said tabs when engaging said slots.

5. A portable head rest according to claim 2 characterized in that said slots are in said resilient sheet, adjacent side edges thereof and side-by-side, and said tabs project forwardly from said front part with the shortest distance between said slots when said resilient sheet is substantially flat being greater than the shortest distance between said tabs when engaging said slots, said tabs being disposed diagonally with respect to said front part and said resilient sheet.

6. A portable head rest according to claim 2 characterized in that said slots are in said resilient sheet, adjacent side edges thereof and side-by-side, and some of said tabs project forwardly from said front part, with the shortest distance between said slots when said resilient sheet is substantially flat, being greater than the shortest distance between said tabs when engaging said slots, said front part also being provided with a slot extending transversely of said front part, and said sheet being provided with a tab, with tongue, extending to the last-named slot with the tongue of said last named tab extending into the last named slot in snug engagement with the wall thereof.
